UNITED STATES PATENT OFFICE

RICHARD M. CRAIG, OF SAN ANTONIO, TEXAS, ASSIGNOR, BY MESNE ASSIGNMENTS, TO
THOMAS W. MENEFEE, OF SAN ANTONIO, TEXAS

DISPLAY APPARATUS

Original application filed December 29, 1925, Serial No. 78,248. Divided and this application filed January 7, 1929. Serial No. 330,937.

This invention relates to display apparatus and more particularly to an advertising sign of the type disclosed in Patent No. 1,698,223, issued January 8, 1929, and of which the present application constitutes a division.

One object of the invention is to provide a sign having figures painted thereon, in pigment colors against a neutral background, other advertising matter being also painted upon the sign in pigment colors and the sign being illuminated by lights emitting spectral colors, having such relation to the pigment colors and so controlled that when the sign is in operation a figure will appear to move across the sign board.

Another object of the invention is to provide a method of and apparatus for not only producing the effect of apparent continuous motion or continuous change in appearance of the subject matter to be displayed, but also displaying the subject matter under pleasing colored lighting conditions, so that, as an advertising medium, the surface to be displayed attracts immediate attention because of the presence of the factors of colored light illumination and animation.

The invention is illustrated in the accompanying drawing wherein is disclosed an embodiment of the invention.

In the drawing, and in the description which is to follow, the invention has been illustrated and will be described as applied to advertising displays, but the principles of the invention are by no means limited to this particular use as they may find embodiment in displays of various characters, and, therefore, what is illustrated and described is to be considered merely as representative of concrete embodiments of the inventive idea and not as restricting the invention to the specific disclosure.

In the description, reference will be made to "display surface" and this term is intended to cover any surface of any character whatsoever upon which there is represented matter to be displayed and regardless of the character of the said matter. Where reference is made to light rays having "different color characteristics" the term is intended to indicate that the light rays are not identical

ly the same but possess such spectral or color difference between themselves as to suit the purposes of the invention. I will also refer to "special colors" and such reference applies to colors of the spectrum as represented by colored light rays. Reference will also be made to "neutral colors" which colors are employed, in the form of pigments, as backgrounds, and by neutral colors is meant such colors as do not materially change under the light rays by which the display surface is illuminated or, in other words, those colors which display no decided color characteristics such as are peculiar to primary colors, and which remain of about the same apparent density under complementary or primary light ray illumination.

In the embodiment of the invention illustrated in the drawing the background areas are of contrasting neutral colors and the display surface is indicated in general by the numeral 19 and has applied thereto suitable pigments of neutral colors to provide background areas indicated one by the numeral 20 and the other by the numeral 21. In this instance, the background area 20 may be black or of any other dark neutral color as for example, dark gray, tobacco brown or Indian red, and the background area 21 is white in color or of any other light neutral color. It will be noted that the background areas 20 and 21 are of contrasting neutral colors, image representations 22 are painted or otherwise represented in red pigment within the background area 20 and represent successive positions assumed by a person running across the board and turning a handspring midway the width thereof, and display matter, such for example as worded advertising matter, indicated by the numeral 23 is represented in red pigment upon the background area 21. A series of sources of red light illumination such for example as electric light bulbs of a red color, indicated by the numeral 25, are arranged above the display surface, each above a respective one of the image representations 22, and blue light bulbs 24 are arranged alternately with the red light bulbs and, therefore, occupy positions above the spaces between relative-

ly adjacent ones of the image representations 22, the red light bulbs 25 being preferably shielded by suitable shielding reflectors as indicated by the numeral 26.

5 The numeral 27 indicates in general a source of current supply from one side of which there is led a conductor wire 28 connected to one terminal of each of the sockets for the red light bulbs 25 and blue light bulbs 24, and from the other side of which there is led a conductor wire 29 connected to the other terminals of the sockets for all of the blue light bulbs 24. A conductor wire 30 is likewise led from the last mentioned side of 10 the source of current supply to the shaft 31 of an automatic flasher indicated by the numeral 32, which, may be of any of the well-known types suitable for the purpose. The numeral 33 indicates a flasher disc which is 15 of insulating material, in this instance, and is mounted concentric to the shaft 31 and carries upon its face a plurality of contacts 34 to be successively engaged by a contact arm 35 fixed upon the shaft 31, conductor 20 wires 36 being led from the contacts 34 to the other terminals of the sockets for the red light bulbs 24.

It will now be observed by reference to the drawing, that, when the display apparatus 25 is in operation, all of the blue light bulbs 24 will be simultaneously and continuously lighted or energized so that the entire display surface is flooded with blue light rays. Therefore, the image representations 22 which are in red will be obliterated inasmuch 30 as they are upon a dark neutral background and likewise inasmuch as the spectral rays under which the images are displayed are of a color complementary to the color in which 35 the images are represented, and, on the other hand, the matter 23 which is depicted in red pigment will stand out substantially black against the white or light neutral background area 21. However, as the flasher 32 is operated, the red light bulbs 25 will be successively 40 lighted in order extending from the right hand end of the display surface to the left hand end thereof and, therefore, the image representations 22 will be successively brought to view individually, the images appearing, through contrast with the dark 45 background area 20, substantially a vivid white and possessing marked brilliancy, due to such contrast. As previously pointed out 50 there is a contrast of background areas in neutral colors and it will be observed that the images 22 as well as the matter 23 are both represented in the same pigment color or, in other words, pigment colors having no visible spectral difference.

60 I have therefore provided a sign which will attract the eye of a person and hold his attention for a comparatively long length of time.

65 What is claimed is:

1. Means for displaying the effect of continuous motion comprising a display surface having a background of a dark neutral color, the said surface bearing, within the bounds of said background, a series of representations of an image in a distinctive pigment color and representing different positions of movement of the image, means for displaying the whole of said surface under light rays of a spectral color in contrast with the color in which the images are represented, and means for displaying said image representations successively and individually under spectral light rays of a color in contrast with the color of the first mentioned rays and not absorbable by the pigment color in which the images are represented. 70

2. Means for displaying the effect of continuous motion comprising a display surface having a background of a dark neutral color, 85 the said surface bearing, within the bounds of said background, a series of representations of an image in a distinctive pigment color and representing different positions of movement of the image, means for displaying the whole of said surface under light rays of a spectral color in contrast with the color in which the images are represented, and means for displaying said image representations successively and individually under 90 spectral light rays of a color corresponding to the color in which the image is represented. 95

3. Means for displaying the effect of continuous motion comprising a display surface having a background of a dark neutral color, 100 the said surface bearing, within the bounds of said background, a series of representations of an image in a distinctive pigment color and representing different positions of movement of the image, means for displaying the whole of said surface under light rays of a spectral color in contrast with the color in which the images are represented, and means for displaying said image representations successively and individually under 105 spectral light rays of a color in contrast with the color of the first mentioned rays and not absorbable by the pigment color in which said images are represented, the said surface having a background area of a light neutral color, the said light neutral background area bearing matter to be represented and which matter is depicted in the same color as that in which the image is represented. 110

115 In testimony whereof I affix my signature. 120
